UNITED STATES PATENT OFFICE

2,408,134

CALCULATING MACHINE

Daniel Broido, Cockfosters, near Barnet, England

Application January 13, 1944, Serial No. 518,044
In Great Britain October 21, 1942

16 Claims. (Cl. 235—61)

1

This invention relates to calculating machines for non-uniform numerical systems comprising interrelated sets of units (such as pounds sterling, shillings and pence).

The object of the invention is to provide a relatively simple calculating machine of the repeated addition type for calculations involving non-uniform numerical systems, the results being correctly expressed in a non-uniform system.

A further object is to provide a calculating machine for non-uniform systems which at once converts all set-up values into all decimal multiples (within the capacity of the machine) expressed in the non-uniform system.

Yet another object is to provide a calculating machine for non-uniform systems with a minimum number of physical representations of decimal multiples of the set-up values by enabling a representation of a digit of a decimal set of units to cooperate selectively with several denominational registering elements of this set of units.

Still a further object is to provide a calculating machine for non-uniform systems with a minimum number of settable selector elements, only one element being required to represent all decimal multiples, within the machine capacity, of each set-up value.

Another object is to provide a calculating machine for non-uniform numerical systems adapted to enter any desired decimal multiple of the set-up factor directly from the settable selector elements into the result register during each working cycle.

A further object is to provide a calculating machine adapted for direct division in non-uniform numerical systems.

Further objects of the invention will become apparent as the description proceeds.

In the accompanying drawings which illustrate a machine made according to the present invention:

Figure 1 is a pence conversion table,

Figure 2 is a shillings conversion table,

Figure 3 is a pounds conversion table,

Figure 4 is a conversion table for fractions of a penny,

Figures 5 and 5A together constitute a front elevation of the machine,

Figures 6 and 6A together constitute a vertical section taken approximately on line VI—VI of Figure 5A,

Figures 7 and 7A together constitute a horizontal section approximately on line VII—VII of Figures 5, 5A,

Figure 8 is a partial section approximately on line VIII—VIII of Figure 6,

2

Figure 9 shows diagrammatically some of the selector plates used in the machine,

Figure 10 shows selector plates of the upper bank,

Figure 11 shows selector plates of the middle bank,

Figure 12 shows selector plates of the lower bank,

Figure 13 shows selector plates for fractions of

10 a penny used in a modification of the invention,

Figure 14 is a partial section through the result register, taken approximately on line XIV—XIV of Figure 6A,

Figure 15 is a section on line XV—XV of

15 Figure 14,

Figure 16 is a partial vertical section approximately on line XVI—XVI of Figure 6A,

Figure 17 is a partial view in the direction of arrow XVII in Figure 5, and

20 Figure 18 shows some selector plates suitable for use in a modification.

General arrangement

The machine illustrated in the drawings comprises, broadly, a shiftable set-up and conversion mechanism, a result register, a feeler mechanism adapted to transfer the set-up values to the result register, a revolution register for indicating the number of said transfers, and driving means 25 and other associated devices. As shown in Figures 6, 6A, and 7, 7A, the various mechanisms are mounted on a base plate 1 in the frame structure 2, 3, and are protected by a cover 4.

Set-up and conversion mechanism

35 As shown in Figures 5, 5A, 6, 6A, and 7, 7A, the set-up mechanism comprises nine setting levers 5, of which five levers are reserved for the pounds denominations (designated $L10^4$ — $L1$), 40 one for the shillings (S), one for pence (D1), and two levers for tenths and hundredths of a penny, respectively ($D10^{-1}$, $D10^{-2}$). All setting levers 5 are rockably mounted on a shaft 6 fixedly supported in side plates 7, 8 of a carriage 9. Forward extensions of levers 5 protrude through slots in carriage cover 10 so as to be rocked into alignment with numerals arranged along the respective slots to indicate the set-up values. Each lever 5 has serrations 11 co-operating with detents 12 rockable on a rod 13 secured in carriage plates 7, 8. Springs 14 hold the detents 12 in engagement with serrations 11, guide plates 15 serving to prevent the detents from slipping off the serrations.

55 Setting levers 5 serve to bring into working position selector plates 16, one of which is pro-

vided for each numeral marked on carriage cover 10 adjacent to the respective slots. These selector plates, which constitute the conversion mechanism and will be fully described hereafter, are arranged in three banks clearly shown in Figure 6. The middle bank comprises L10², S, and D10⁻² selector plates 16 which are rockably supported on shaft 6 by the respective setting levers 5 and bails 17 (Figures 7, 7A). The upper bank comprises L10³, L1, and D10⁻¹ selector plates 16 mounted in bails 18 rockable on shaft 19 secured in carriage plates 7, 8. One of the bails 18 supporting each set of plates 16 is connected by a link 20 to the respective setting lever 5 on shaft 6. The lower bank comprises L10⁴, L10, and D1 selector plates 16 mounted in bails 21 rockable on shaft 22 and connected by links 23 to respective levers 5. Selector plates 16 co-act with three banks of sensing pins 24 mounted for horizontal movement opposite the respective banks of selector plates. By aligning the setting levers 5 with certain numerals on carriage cover 10, the corresponding selector plates 16 are brought into working position opposite the sensing pins 24 of the respective bank.

A restoring bar 25 pivoted on shaft 6 has a plate 26 protruding through a slot in carriage cover 10. When knob 27 fixed to plate 26 is lifted upwards, bar 25 rotates around shaft 6 and restores all setting levers 5 into the initial position.

Carriage 9 is mounted for transverse movement on rollers 28 running in rails 29, 30. A spring 31 mounted in barrel 32 runs over pulley 33 (Figure 7) and is secured to carriage plate 8, so as to pull the carriage to the left. An escape-
ment pawl 34 pivoted in carriage base 9 co-acts with a rack 35 fixed to base plate 1. A shift lever 36 pivoted at 37 in carriage base 9 protrudes forwardly through a slot in carriage cover 10 and has a knob 38; spring 39 tends to rock the lever 36 clockwise as viewed in Figure 6. As shown in Figure 8, the rear end of lever 36 engages a slot in pawl 34, thus rocking it anti-clockwise so that a nose 40 formed on pawl 34 engages the teeth of rack 35. When knob 38 is depressed, the rear end of lever 36 swings the pawl 34 clockwise as viewed in Figure 8, thus disengaging the nose 40 from rack 35; the carriage is then shifted by spring 31 approximately half a step to the left, whereupon a second nose 41 on pawl 34 engages the rack. When knob 38 is released, lever 36 and pawl 34 are restored by spring 39, and nose 41 disengages rack 35, whereupon the carriage is again shifted for approximately half a step until nose 40 re-engages rack 35. Thus, the total movement of the carriage 9 upon each depression of knob 38 equals the pitch of rack 35. The carriage is arranged to move a maximum of seven steps to the left from the initial position, and four steps to the right thereof. Each step of the carriage is equal to the distance between two adjacent register wheels of the pounds set of units, as will be fully explained hereafter. As shown in Figures 5, 5A, the various positions of the carriage are indicated by a pointer 42 formed on machine cover 4, which pointer co-acts with numerals +1 to +7 on carriage cover 10 to indicate positions to the left from the initial position designated 0, and with numerals -1 to -4 to indicate the shift to the right.

Return movement of carriage 9 is effected by knobs 43 on a hand wheel 44 protruding through a slot in machine cover 4. Hand wheel 44 is fixed to a gear 45 secured to one of rollers 28. Gear 45 meshes with a rack 46 formed on front

rail 29. By turning the hand wheel 44 clockwise (as viewed in Figure 5A) the carriage 9 is shifted to the right.

The carriage shift is utilised to multiply the set-up values by decimal multiples, i. e. by 10, 100, 1000, and so forth when shifted to the left, or by 0.1, 0.01, and so forth when shifted to the right. This arrangement of the set-up mechanism provides, in the present embodiment, for a capacity up to 99, 999, 999.9999 for the multiplier, and up to £99,999.19:11.99d. for the multiplicand. The product may comprise thirteen pounds denominations, two shillings denominations, pence denomination, and six denominations of decimal fractions of a penny. A sensing pin 24 is provided for each bank of selector plates 16 for each of these twenty-two possible result denominations. The transverse distance between the sensing pins 24, as may be seen from Figures 9 and 7, is the same (namely, equal to the carriage step) between the pins associated with L10¹¹—L1 and D10⁻¹—D10⁻⁶ denominations, but it is different to the distance between sensing pins L1, S10, S1, D1, and D10⁻¹. More explicitly stated, the distance between sensing pins of any two non-decimal denominations (tens of shillings, units of shillings, or pence) is different from the carriage shift or any whole multiple of the carriage shift. Similarly, the transverse distance between the sensing pin of a non-decimal denomination and the sensing pin of any decimal denomination (pounds or decimal fractions of a penny, respectively) is different from the carriage shift or any whole multiple thereof. Further, the transverse distance between any sensing pins of a decimal notation (pounds) and of another decimal notation (decimal fractions of a penny) is also different from the carriage shift or any whole multiple thereof. On the other hand, the transverse distance between any two adjacent sensing pins associated with the same decimal notation (pounds or decimal fractions of a penny, respectively) is substantially equal to the carriage shift. The importance of this arrangement will become apparent as the description proceeds.

Selector plates 16, except those reserved for the zero values, are notched so as to represent the converted decimal multiples of the respective set-up values, that is the products of the set-up value by successive powers of 10, expressed in the interrelated denominations. The arrangement of these notches will be evident from an inspection of Figure 9. It shows three selector plates 16 of the lower bank, namely those associated with £40,000, £10, and 3d., designated respectively L10⁴(4), L10(1), and D1(3). Sensing pins 24 are represented by thick vertical lines designated L10¹¹—D10⁻² in the upper half of the drawing (which serves to illustrate the carriage shift to the left), and L10⁷—D10⁻⁶ in the lower part (which illustrates carriage shift to the right). The transverse positions of the carriage are designated by numerals 0 to +7 and -1 to -4 along the right-hand edge of the drawing. Selector plates 16 in line with each of these numerals are shown in their actual positions relatively to the sensing pins 24 in the respective transverse positions of the carriage.

Considering first the pence selector plate D1(3), it will be seen that in the initial position 0 only one sensing pin 24 will be aligned with a notch in the plate, namely the D1 pin; the depth of this particular notch is such as to represent 75 "3," i. e., it is three "unit steps" deep, as indi-

cated by the numeral "3" adjacent to this notch. The sensing pins **24** are arranged to move into the notches and to transfer the values associated with each notch to the corresponding numeral wheel of the result register, as will be fully described hereafter. Evidently the amount of movement of each sensing pin, viz., the amount transferred to the respective register wheel, is determined by the depth of the respective notch. If a sensing pin does not encounter a notch, i. e., is stopped by the edge of the selector plate, it does not move appreciably, and the associated register wheel is not operated at all. In the present case, only the **D1** pin will enter a notch, and thus it will transfer the value "3" associated with this notch to the pence wheel of the result register.

When the **D1(3)** selector plate is shifted one step to the left into position +1, sensing pins **S1** and **D1** will be aligned with notches representing "2" and "6" respectively; consequently, the amount $2/6d. = 3d. \times 10$ will be entered into the register. When the selector plate is in position +2, the **L1** and **S1** pins will be aligned with notches "1" and "5" respectively, and the amount $\text{£}1:5:0 = 3d. \times 100$ will be registered. Similarly, when the selector plate is in position +3, the amount $\text{£}12:10:0 = 3d. \times 1000$ will be registered by pins **L10**, **L1**, and **S10** entering notches "1," "2," and "1" respectively. When the plate is in position +4, the amount $\text{£}125:0:0 = 3d. \times 10,000$ will be registered by pins **L10²**, **L10** and **L1** in co-operation with notches "1," "2," "5," respectively. These same notches operate, when the plate is shifted into position +5, +6 or +7, the respective pins of the next higher denominations so as to register $\text{£}1250:0:0 = 3d. \times 100,000$; $\text{£}12,500 = 3d. \times 1,000,000$; and $\text{£}125,000 = 3d. \times 10,000,000$, respectively, since, as already mentioned, the transverse distance between two adjacent sensing pins associated with pounds register wheels equals the transverse step of the carriage. It will now be seen why the different spacing between the sensing pins of various denominations is necessary: the notches representing pence values must not be aligned with pins **24** associated with shillings or pounds register wheels, and vice versa. Similarly, notches representing pounds values must not be aligned with sensing pins associated with denominations of fractions of a penny, and vice-versa.

Considering the shift of the **D1(3)** selector plate to the right into position -1, -2, -3, or -4, only one notch in this plate, namely that representing "3," will be aligned with sensing pin **D10⁻¹**, **D10⁻²**, **D10⁻³**, or **D10⁻⁴**, respectively. Thus, the value 0.3d., or 0.03d., or 0.003d., or 0.0003d., as the case may be, will be entered into the register.

Those sensing pins **24** which are not aligned with any selector plate **16** (i. e., the **D10⁻²** pin when the plate **D1(3)** is in the +7 position) are rendered inoperative by means which will be described in due course.

Considering now the selector plate **L10(1)**, in the initial position 0 only one notch designated "1," which is one step deep, is aligned with a sensing pin, namely that of the **L10** denomination. Consequently, the amount $\text{£}10$ will be registered. When this plate is shifted to the left, this same notch "1" will be aligned with pins **24** of the higher pounds denominations **L10²**—**L10⁸**; thus £100, £1,000, £10,000 and so forth will be registered when the plate is in position +1, +2, +3, and so forth, respectively. In position -1 this

notch, being aligned with the **L1** pin, will cause it to register £1. When the plate is in position -2, this notch "1" is not aligned with any pin **24**; instead, another notch "2," which is two steps deep, will be aligned with the **S1** sensing pin which thus enters into the register $2/— = \text{£}10 \times 0.01$. In position -3 notches "2" and "4" will be aligned with pins **D1**, **D10⁻¹** respectively, which will register $2.4d. = \text{£}10 \times 0.001$. Finally, in position -4 notches "2" and "4" will co-act with pins **D10⁻¹**, and **D10⁻²**, respectively, to enter into the register $0.24d. = \text{£}10 \times 0.0001$.

The arrangement of the selector plate **L10⁴(4)** will be readily understood, in the light of the above explanation, from an inspection of Figure 9. Other selector plates **16** are notched similarly to represent the respective decimal multiples expressed in the final denominations. It will be noted that if a notch represents a digit of a decimal set of units (pounds or decimals of a penny), this notch may be aligned, due to carriage shift, with sensing pins of several denominations of this set of units, but if a notch represents a digit of a non-decimal denomination (tens of shillings, or units of shillings, or pence), this notch will be aligned only with the sensing pin of this particular denomination. Similarly, notch representing a pounds value may be aligned with any sensing pin associated with a pounds denomination but never with a sensing pin associated with a denomination of fractions of a penny, and vice-versa.

All notches in the various selector plates of the same bank are sensed simultaneously, as will be described hereafter. Thus, assuming it is desired to multiply $\text{£}40,010:0:3d. \times 10.001$, the setting levers **L10⁴**, **L10**, and **D1** are adjusted in line with numerals "4," "1," and "3" on carriage cover **10**, respectively. Thus, selector plates shown in Figure 9 are brought into working position in alignment with sensing pins **24** of the lower bank. The carriage is then shifted into position +1, and the decimal multiple

$\text{£}400,100:2:6d. = \text{£}40,010:0:3d. \times 10$

is registered as described above. The carriage is then shifted into position -3, and the amount $\text{£}40:0:2.403d. = \text{£}40,010:0:3d. \times 0.001$ is added to the register, which will show the result as the sum of these two decimal multiples, namely

$\text{£}400,140:2:8.403d.$

The converted values of all decimal multiples of the set-up values within the capacity of the machine are shown in Figure 1 (for pence), Figure 2 (for shillings), and Figure 3 (for pounds). Columns -2, -3, -4 in Figure 1 are left blank as the numerical values of the respective decimal multiples are identical with those of column -1, the decimal point being shifted in each successive column one step to the left. It will be understood that although all values shown in Figures 1-3 are represented by notched selector plates **16**, the total number of notches in plates

16 is considerably less than the number of digits contained in Figures 1-3, since one and the same notch may represent a digit of several denominations of a decimal set of units. Thus, a single notch designated "4" on plate **L10⁴(4)** in Figure 9 may represent, according to the position of the carriage, £40,000 or £4,000 or £4, and so forth.

Selector plates **16** of the upper, centre, and lower bank are shown in Figures 10, 11, 12, respectively. In these figures, the vertical lines of numerals designate the set-up values associated

with respective selector plates; the dotted vertical lines approximately in the middle of the drawings indicate the position of the D1 sensing pin 24,

The capacity of the machine made according to the invention is not limited to that specified above. Both the number of carriage shifts (which determines the multiplier) and the number of denominational sets of selector plates (which determines the set-up factor, e. g. multiplicand) may be increased or decreased as desired. The notches in the selector plates may be arranged to suit not only the pounds sterling system of notation, but any other numerical system, for instance the avoirdupois system, Indian currency, and so forth. In a modified conversion mechanism made according to the present invention the selector plates D10⁻¹ and D10⁻² may be replaced by sixteen selector plates representing the decimal multiples of vulgar fractions $\frac{1}{16}$ to $\frac{15}{16}$ of a penny. These multiples are shown in Figure 4, columns -4 to -1 of which are left blank for the same reason as stated with reference to Figure 1. The corresponding selector plates are shown in Figure 13, wherein Df signifies "fractions of a penny" denomination. It is evident that with suitable alterations the selector plates Df may be made to represent any other fractions instead of sixteenths.

Feeler mechanism

As already described, the notched selector plates 16 determine the amount of movement of sensing pins 24 during the working cycle of the machine. As shown in Figures 6, 6A, sensing pins 24 co-act with three-pronged feelers 47 pivoted at 48 in gear sectors 49 rockable on a shaft 50 fixed in the supporting structure 2, 3 (see also Figures 7, 7A). Each gear sector 49 co-operates with a numeral wheel of the result register as will be described hereafter. Rockably mounted on shaft 50 adjacent to each gear sector 49 is a bracket 51 which has a pin 52 engaging a slot in gear sector 49 (see also Figure 14); a spring 53 connects each sector with its bracket. A stronger spring 54 anchored in a spring bar 55 tends to swing each bracket 51 anti-clockwise as viewed in Figure 6A, so that an abutment 56 thereon abuts against a restoring bar 57. This bar is common to all brackets 51; it extends across the machine and is at each end pivotally mounted on shaft 50, a spring 58 keeping a roller 59 journalled at each side of bar 57 in contact with a triple cam 60. Thus, during each revolution of cams 60 the brackets 51 and gear sectors 49 are reciprocated three times.

A link 61 is pivoted at 62 to each feeler 47. The lower ends of links 61 are pivoted on a common rod 63 supported in a bar 64 rockable on shaft 50; a roller 65 journalled at either end of bar 64 is biased on to a cam 66 by a spring 67. Cams 66 are so shaped as to rock the feelers 47 prior to the first forward (anti-clockwise) movement of brackets 51 and gear sectors 49 so that the upper prongs 68 of feelers 47 are aligned with the upper bank of sensing pins 24, whereas the two lower prongs are not aligned with their respective banks of pins 24; prior to the second forward movement feelers 47 are rocked so that the middle prongs 69 are aligned with the middle bank of pins 24, as shown in Figures 6, 6A; finally, prior to the third forward stroke of feelers 47 they are rocked by cams 66 so that their lower prongs 70 are aligned with the lower bank of pins 24, the other prongs 68, 69 being out of alignment with their respective banks of sensing pins

24. Thus, during a complete revolution of cams 60, 66, the three banks of pins 24 are contacted in succession by feelers 47 and pushed forward into the notches of selector bars 16. As the extent of movement of pins 24 is determined by the depth of notches they encounter, the amount of movement of feelers 47, gear sectors 49, and brackets 51 is also determined by these notches in the selector plates; consequently, the amount of movement imparted by each gear sector 49 to the register wheel which it drives in a manner to be described hereafter is also determined by the numerical values represented by the respective notches.

Shaft 50, rod 63, and pivots 48, 62 form a parallelogram, so that prongs 68, 69, 70 of feelers 47 are reciprocated along parallel and substantially straight lines. Guides 71, 72 serve to ensure proper alignment of the feelers 47 with sensing pins 24.

The reason for the three-bank arrangement of selector plates 16 and sensing pins 24, and for the successive reading-out of these three banks by a triple movement of feelers 47 and gear sectors 49 will be apparent after the following consideration. Assuming it is desired to multiply 1 1/4d. set up as 1.25d. by 100, all three sub-products: 1d. $\times$ 100 = 8/4d.; 0.2d. $\times$ 100 = 1/8d.; 0.05d. $\times$ 100 = 5d.; contain pence values to be entered into the same register wheel D1. Evidently, this cannot be done simultaneously; each sub-product must be registered separately, the whole operation to obtain the result 10/5d. being completed in three successive steps.

Prongs 68, 69, 70 on feelers 47 are so shaped that when they are rocked into alignment with their respective sensing pins 24, the latter are pushed forward slightly until they encounter the edge of a selector plate 16, or just begin to enter a notch therein, as the case may be. When the feelers 47 are released for forward movement by cams 60, those feelers which are stopped by their sensing pins encountering the edge of a selector plate 16 do not move appreciably, but their associated brackets 51 move a distance determined by the length of slots engaged by pins 52 in gear sectors 49, whereupon the brackets 51 are also stopped. This slight independent movement of brackets 51 is utilised to effect the carrying operation as will be described hereafter.

Sensing pins 24 are restored after each forward stroke of feelers 47 by a restoring plate 73 fixed at each side of the machine to a slide 74. Slots in slides 74 embrace guide pins 75 secured to side plates 2, 3. Pin 76 fixed to each slide 74 is engaged by a fork 77 fixed at each end of the restoring bar 57 operated by cams 60 as described above. Thus, when bar 57 and feelers 47 begin to move forward, the restoring plate 73 also moves forward to allow for free movement of sensing pins 24. On return stroke the plate 73 engages shoulders 78 formed on pins 24 and restores them to initial position shown in Figure 6.

Gear sectors 47 have lower extensions 79 adapted to co-act with locking pawls 80 pivoted in a bar 81 fixed to base plate 1. Springs 82 bias the pawls 80 into engagement with extensions 79, thus locking the gear sectors 47 and preventing their forward movement when released by cams 60. Locking pawls 80 are controlled by a plate 83 fixed to carriage base 9. The arrangement is such that when the carriage 9 is aligned with certain gear sectors 49, the plate 83 rocks the respective pawls 80 to unlock these gear sectors 49 for co-operation with the selector

plates 16, while those sectors 49 which are not aligned with the selector plates remain locked by their pawls 80.

Result register

Each gear sector 49 drives a denominational unit of the result register as shown in Figure 6A. As all these units are substantially alike, only one such unit is shown in section in Figure 14.

Gear sectors 49 mesh with small pinions 84 rotatable on shaft 85 supported in the frame structure 2, 3. Rigidly fixed to each pinion 84 is a disc 86 and a washer 87, and a gear 88 is rotatably mounted on disc 86. As clearly shown in Figure 15, gears 88 have internal ratchet teeth 89; a driving spring 90 fixed to the hub of each disc 86 engages the ratchet teeth 89. During the forward stroke of gear sectors 49 the gears 88 remain stationary, as the driving springs 90 rotate within the ratchets 89 (clockwise as viewed in Figure 15) without engaging the ratchet teeth. During the return stroke of sectors 49 the driving springs 90 engage the ratchet teeth 89 and thus rotate the gears 88. Gears 88 mesh with idler gears 91 (Figures 14 and 6A) rotatable on shaft 92 supported at each end in a plate 93 (Figures 6A and 16). A second series of idler gears 94 is rotatably mounted on a shaft 95 also supported in plates 93. These plates 93 are pivoted at 96 in the supporting structure of the machine; they can be rocked around their pivots 96 (by means to be described hereafter) in order to drive register gears 97 positively or negatively as desired. When the machine is conditioned for addition or multiplication, the idlers 91, 94 are in the position shown in Figure 6A; idlers 94 are not in mesh with register gears 97 which are driven directly by idlers 91 "positively" viz. anti-clockwise. When the machine is conditioned for subtraction or division, idlers 91, 94 are rocked into position indicated by dash-dotted lines in Figure 6A; idlers 91 are not in mesh with register gears 97 but idlers 94 are; consequently, gears 97 are driven "negatively," viz. clockwise as viewed in Figure 6A.

Register gears 97 are rotatable on shaft 98 journaled in the supporting structure 2, 3. Rigidly fixed to each gear 97 is a locating gear 99 (Figure 14), a numeral wheel 100, and a carry pinion 101. The numerals on wheels 100 are visible through apertures 102 in the machine cover 4 (Figure 5, 5A and 6).

Locating gears 99 co-operate with detents 103 (Figure 6) rockable on a rod 104 and biased by springs 105 housed in a spring bar 106. All locating gears 99 have ten teeth except that of the pence denomination D1 which has twelve teeth according to 0-11 pence. In order to produce a $\frac{1}{12}$ step of the D1 numeral wheel 100 as compared with the $\frac{1}{10}$ step of all other wheels 100, those notches in the selector bars 16 which are reserved for co-operation with the D1 feeler 47 are made correspondingly shallower, each unit step of these notches being $\frac{1}{2}$ of the unit step of all other notches.

Carry pinions 101 each have one tooth except the S10 pinion which has five teeth, since the S10 numeral wheel 100 must carry five times during each complete revolution. Pinions 101 co-act with carry pawls 107 (Figures 6A and 14) which, like detents 103, are rockable on rod 104 and are biased by springs similar to detent springs 105. The upper parts of pawls 107 are shaped like detents 103, but they are bent sideways as indicated in Figure 14. Each carry pawl 107 has an arm 108 (Figure 6A) co-acting with an abutment

109 formed on gear sector 49 of the next higher denomination. A second arm 110 on pawl 107 contacts with a latch 111 rockable on a rod 112 and biased by a spring 113 housed in spring bar 55.

- 5 When a carry has to be effected, carry pinion 101 causes carry pawl 107 to swing out clockwise as viewed in Figure 6A, so that abutment 109 on gear sector 49 of the next higher denomination is no more supported by arm 108; this sector 49 10 swings under the influence of its spring 53 until its abutment 109 encounters a shoulder 114 formed on arm 108 as to allow for one-step movement of gear sector 49, which thus drives the associated numeral wheel 100 one step so as to effect the carry. The length of slots in gear sectors 49 embracing pins 52 in brackets 51 is also chosen accordingly to allow for one-step movement of gear sectors 49 independently of brackets 51.
- 20 When carry pawl 107 swings clockwise to effect the carry, latch 111 is also rocked clockwise by its spring 113 so as to lock the pawl 107 in the "carry" position. Thus, if a carry has to be effected while the gear sector 49 of the next higher denomination is being moved by the restoring bar 57, the carry pawl 107 will remain in the "carry" position until after the sector 49 returns to its initial position. As the abutment 109 on sector 49 will not encounter the end of arm 108, the sector will continue to move clockwise until its abutment 109 runs up against shoulder 114, thus effecting the carry. At the beginning of the next forward stroke of gear sectors 49, a restoring bar 115 pivoted at each end at 116 restores all 35 previously operated latches 111. It has rollers 117 co-acting with cams 60; it is restored by springs 118.

- 40 It will be understood that whenever cams 60 cause brackets 51 to swing forward (anti-clockwise as viewed in Figure 6A), brackets 51 restore those gear sectors 49 which have previously effected the carry operation into position shown in Figure 6A, whereupon sectors 49 and feelers 47 either continue their forward stroke or remain stationary, according to whether the corresponding sensing pins 24 encounter notches in selector plates 16 or not.

- 45 Numerals wheels 100 are zeroised in a conventional manner by means of a spring-loaded comb bar 119 (Figure 14) slidable in a key-way in shaft 98. Elevations 120 on bar 119 co-operate with lugs 121 formed on register gears 97. The zeroising operation is effected by turning a clearing handle 122 (Figure 5A); a cam-like recess in one of the bearings (not shown) of the register shaft 55 98 causes the comb-bar 119 to shift slightly to the left as viewed in Figure 14, whereupon elevations 120 pick up lugs 121 and restore the numeral wheels 100 to the initial positions. Comb-bar 119 is then restored by its spring into the recess in the bearing. The result register comprises two more numeral wheels L10¹² and L10¹³ (Figure 5) than is actually required for the capacity of the machine. These two additional numeral wheels serve to store the carries from the L10¹¹ wheel. They are each operated by a gear sector 49 and brackets 51 which do not have a feeler 47 (Figures 7, 7A).

Revolution register

- 70 As shown in Figures 6A and 5, the revolution register comprises numeral wheels 123 rotatable on shaft 124 journaled in the supporting structure; they are visible through apertures 125 in the machine cover 4. Each numeral wheel 123 has a gear 126 adapted to be located by a detent

127 rockable on shaft 128 and biased by a spring 129 housed in a spring bar 130. For the purpose of carry each numeral wheel 123 has a one-tooth pinion (not shown) co-acting with a customary rocker 131 pivoted on shaft 128. Gears 126 mesh with gears 132 rotatable on a rod 133 adjacent to rockers 131. Gears 132 are driven by a driver 134 slidable along a flat shaft 135 journalled in the supporting structure. Driver 134 is held between the left-hand carriage plate 7 and a bracket 136 secured hereto. As the carriage 9 is stepped transversely of the machine, driver 134 is also shifted along its shaft 135 into alignment with the respective gear 132. One numeral wheel 123 with gears 126, 132 is provided for each possible shift of the carriage, as indicated by numerals -4 to +7 adjacent to apertures 125 (Figures 5, 5A). An additional numeral wheel 123 designated +8 is not driven by the driver 134; it serves to indicate the number of the operation when the carriage is in the last, viz. +7 position, if this number exceeds nine; it is operated by the carry device only, as will be presently described.

Fixed to shaft 135 is a gear 137 (Figure 6) meshing with an idler gear 138 journalled in the side frame 2; this idler 138 meshes with a gear 139 fixed to a carry shaft 140 journalled in the frame structure 2, 3, and driven in a manner to be described hereafter. Carry shaft 140 has the usual spring-loaded rocking pins 141 and restoring cams 142 cooperating in the well known manner with rockers 131 for the purpose of the carry operation. Briefly, in order to effect a carry the one-tooth pinion on numeral wheel 123 pushes the associated rocker 131 downwards around its pivot 128; the lower end of rocker 131 is so sloped as to cause the associated pin 141 to swing out sideways and to drive the idler 132 of the next higher denomination one step, thus effecting the carry. Rocking pin 141 is then restored by its spring, and the rocker 131 is restored by its associated cam 142 on shaft 140.

The revolution register is cleared in the same manner as the result register, by means of a comb-bar 143 and a clearing handle 144 (Figure 5A).

Driving and operating means

The machine is operated by means of a handle 145 and crank 146 journalled in a bearing 147 (Figure 16) in the right-hand side frame 3. Gear 148 fixed to crank 146 meshes with gear 149 rigid on shaft 150 which carries the cams 60, 66 and is journalled in the supporting structure 2, 3. Handle 145 is rotated in one direction only (clockwise) both for positive and negative operations. A suitably shaped spring-loaded pawl 151 (Figure 7A) is arranged to co-operate with gear 148 in order to prevent a rotation in the wrong (anti-clockwise) direction.

Gear 148 further meshes with a double gear 152 (Figure 16) journalled in side frame 3. This double gear 152 meshes with a clutch gear 153 rotatable on sleeve 154 on the flat carry shaft 140. Gear 152 further meshes with an idler gear 155 journalled in frame 3 and meshing with another clutch gear 156 rotatable on sleeve 157 on shaft 140. Thus, when the handle 145 is rotated, clutch gears 153, 156 rotate in opposite directions. Slidably mounted on shaft 140 between the gears 153, 156 is a dog clutch 158 which can be shifted by a clutch fork 159 pivoted at 160 in a bracket 161 into engagement either with gear 156 (for "positive" drive of carry shaft 140) or with gear 153 (for "negative" drive). For this purpose the up-

per end of clutch fork 159 carries a roller 162 co-acting with a double cam 163 fixed to shaft 128 journalled in the frame structure 2, 3. Also fixed to shaft 128 are two internal cams 164 (see also Figure 6A) adapted to co-operate with rollers 165 on plates 93 which support shafts 92, 95 of idlers 91, 94 of the result register. Fixed to shaft 128 is a handle 166 (Figures 5 and 17) which can be set to any one of three positions designated "X+", "-", and "+". When the handle 166 is set to position "X+", the machine is conditioned for multiplication and addition; clutch 158 is in the position shown in Figure 16, cams 164 and idlers 91, 94 are in the position shown in Figure 6A. Consequently, the entries into the result register and into the revolution register are positive, numeral wheels 100 and 123 being driven anti-clockwise as viewed in Figure 6A.

When the handle 166 is set to the position "-", the machine is conditioned for subtraction such as occurs during multiplication when using the method of "short-cutting." In this position of handle 166, cams 164 rock idlers 91, 94 so that both idlers are included in the gear trains driving the numeral wheels 100, thus reversing their direction. Clutch 158 is shifted into engagement with clutch gear 153, thus reversing the rotation of carry shaft 140 and driver shaft 135. Consequently, the entries into both registers are made negative.

When the handle 166 is set to the "-" position, the machine is conditioned for division. Cam 163, when in this position, causes clutch 158 to return into engagement with clutch gear 156; cams 164 are so shaped that they retain both idlers 91, 94 in working positions. Consequently the entries into the result register are negative, while the entries into the revolution register are made positive.

Various devices are incorporated in the machine in order to ensure its correct operation. However, as these devices are not necessary for a proper understanding of the invention, they have not been described in the specification and are not shown in the drawings. It is sufficient to state that a locking device is provided to prevent a shift of the carriage when the operating handle 145 is not in its initial position and, reversely, to lock the handle while the carriage is in motion; a device adapted to lock the operating handle 145 when either of the clearing handles 122, 144 is not in the initial position; a device adapted to prevent a re-setting of levers 5 while the handle 145 is being turned; and means for ensuring a proper positioning of the control handle 166 before the operating handle 145 can be turned. Other well-known devices such as additional registers, printing devices, and so forth may be incorporated in the machine without departing from the spirit of the present invention.

Operation

An example of a simple multiplication has been already given in connection with Figure 9.

Assuming now it is desired to multiply £40,010:0:3d. by 19.9, it is usual to multiply by 20 and to subtract the product by 0.1, according to the "short-cutting" method. The multiplicand £40,010:0:3d. is set up by means of setting levers 5 as already described, and the machine is conditioned for additive multiplication by setting the control handle 166 to "X+." Carriage 9 is then shifted to position +1 by depressing the shift knob 38, and the operating handle 145 is turned twice. As already described, the amount £400,100:2:6d. will be picked up by feelers 47

during each revolution of handle 145 and cam shaft 150 and entered into the result register positively through gear sectors 49, pinions 84, driving springs 90, gears 88, idlers 91, and gears 97; numeral wheels 100 will then show the double amount, namely £800,200:5:0d. the carry from the D1 wheel to the S1 wheel being effected as described above. The revolution register has been driven through gears 148, 152, 155, 156, clutch 158, carry shaft 140, gears 139, 138, 137, shaft 135, and driver 134; after the second revolution of handle 145 the revolution register will show "20." The carriage is then shifted to position -1 by turning the hand wheel 44, the control handle 166 is set to "-" and the operating handle 145 is turned once. The amount £4,001:0:0.3d. will be picked up by feelers 47 and entered into the result register negatively through gear sectors 49, pinions 84, springs 90, gears 88, idlers 91, 94, and gears 97; numeral wheels 100 will then show the result of the calculation as £796,199:4:11.7d., the carry being effected in the same manner as before but negatively, due to the reversal of wheels 100. Carry shaft 140 has been driven during the negative revolution through gears 148, 152, 153, and clutch 158, and the driver 134 has entered "1" negatively into the -1 numeral wheel 123, thus turning it from "0" to "9" and effecting the carry to the "0" numeral wheel 123 and turning it to "9." Consequently, the "0" numeral wheel 123 has effected a carry to the +1 wheel, turning it to "1." Thus, on completion of the negative revolution the revolution register shows the multiplier, viz. 19.9.

Assuming now it is desired to divide £894:12:1d. by £38:17:11d. Control handle 166 being set to "X+" and the carriage being in the initial position, the dividend £894:12:1d. is set up by means of setting levers 5 and is transferred to the result register by a single revolution of handle 145. Now, the revolution register is cleared by turning the handle 144, setting levers 5 are re-set according to the divisor £38:17:11d. and the control handle 166 set to "+." As the dividend is obviously greater than nine times the divisor, the carriage is shifted to the +1 position and the operating handle 145 is rotated. In the course of the first revolution the amount £38:17:11d. $\times 10 =$ £383:19:2d. is negatively entered into the result register (through gear sectors 49, pinions 84, gears 88, idlers 91, 94) and thus subtracted from the dividend already in the register, which will then show £505:12:11d. During the second revolution the figure £383:19:2d. is again subtracted, and the result register will show £116:13:9d. Seeing that "11" is less than "38," the carriage is shifted to the initial position "0" and the handle 145 is again rotated. In this position of the carriage each revolution subtracts the divisor £38:17:1d. from the registered amount, and it will be found that after three revolutions the result register will show zero. The revolution register has been driven positively through gears 148, 152, 155, 156, clutch 158, shaft 140, gears 139, 138, 137, shaft 135 and driver 134, namely the "+1" numeral wheel 123 two steps and the "0" numeral wheel three steps. Consequently, the revolution register now shows the quotient "23."

To take an example of a percentage calculation, supposing it is desired to add 3% to £175:17:11d., this amount is set up and, control handle 166 being on "X+" and the carriage being in the initial position, the operating handle 145 is turned once; the result register then shows

£175:17:11d., and the revolution register shows "1." The carriage is then shifted to the -2 position and the handle 145 turned three times, thus adding the amount £175:17:11d. $\times 0.03 =$ £5:5:6.45d. to the result register, which thus will show the result £181:3:5.45d., and the revolution register will show "1.03."

Percentage method may be used to divide sterling amounts by decimal amounts. For instance, 10 assuming it is desired to divide £97:4:9.5d. by 25, obviously $\frac{1}{25} = \frac{4}{100} = 4\%$; consequently £97:4:9.5d. is set up and the carriage is shifted to -2 position; control handle 166 being on "X+," operating handle 145 is turned four times. The result register then shows the quotient £3:17:9.5d. and the revolution register shows "0.04" which is the reciprocal value of the divisor 25.

It is evident that decimal calculations may be carried out in the pounds section of the machine in the usual way.

It will be evident from the foregoing that as the machine made according to the present invention incorporates physical representations of decimal multiples of the set-up factor, the second factor of a calculation must necessarily be a decimal amount or, if it is not a decimal amount, it must be converted into a decimal amount. This may be done by means of tables, or by means of an automatic conversion device, for instance of the type described in my British patent specification No. 493,277. Without departing from the spirit of the present invention, the machine described above may be modified in many ways. Instead of being driven by hand it may be arranged to be driven by a motor. Setting levers 5 may be replaced by a suitable key-board arrangement. Features known in the art as automatic multiplication and automatic division may be incorporated in the machine. Manual operation 35 of the machine may be replaced by an automatic device controlled by records sensed mechanically, electrically, or by means of light, for example as described in my prior patent specification No. 521,871. Instead of being shiftable together with 40 the conversion mechanism, the set-up mechanism may be made stationary. The conversion mechanism may be arranged in a fixed position, and the feeler mechanism and/or the result register may be made shiftable. Instead of being 45 arranged in three banks, the selector plates may be arranged differently according to the capacity of the machine. Further possible modifications will be apparent to those skilled in the art.

In a modification of the invention adapted for 55 Indian currency one bank of selector plates may be reserved for rupees, thousands of rupees and higher denominations, if any, of rupees; the second bank may comprise hundreds of rupees and annas (1 rupee = 16 annas); and the third bank 60 may be reserved for tens of rupees and pies (1 anna = 4 pies). The set-up mechanism will be modified accordingly, the result register containing numeral wheels 100 having 0-9 numerals for various rupee denominations, a wheel with 0-15 65 numerals for annas, a wheel with 0-3 numerals for pies, and wheels with 0-9 numerals for decimals of a pie. Similarly, in a machine adapted for units of length, one bank may contain inches and all yards denominations except the units, the 70 second bank containing selector plates for units of yards, and the third bank being reserved for feet, the set-up mechanism and the result register being arranged accordingly. In a similar manner, in a machine designed to calculate hours 75 and minutes, one bank may comprise selector

plates for hours (units, thousands, and higher denominations and tenths-of-a-minute, another bank those for minutes and tens of hours, and a third bank those for tens of minutes and hundreds of hours; in this case, the result register will comprise wheels 100 with 0-9 numerals for all hours denominations, minutes, and decimals of a minute, and a wheel with 0-5 numerals for tens of minutes. In a machine with a small capacity only two banks of selector plates will be required.

A machine made according to the invention for calculation of weights may have four banks of selector plates 16 as shown in Figure 18. One bank may comprise selector plates for tons, hundredweights, and ounces, of which those for 1 t., 19 cwt., and 15 oz. are shown; the next bank may comprise selector plates for stones, the plate associated with 7 st. being shown in the drawings; the next bank may be reserved for pounds, the 13 lb. plate being shown; and the fourth bank may comprise selector plates for drachms, the plate for 15 drm. being shown in the drawings. Sensing pins 24, of which only those for tens of tons, tons, hundredweights, stones, pounds, ounces, and drachms are indicated in Figure 18, are adapted to coat with four-pronged feelers 47; cams 66 have four elevations, and cams 60 are made accordingly to sense the four banks of selector plates in succession during each revolution of cam shaft 150. The set-up mechanism may contain setting levers 5 arranged according to the machine capacity, and the result register may contain numeral wheels 100 with numerals 0-9 for all tons denominations, a wheel for 0-19 cwt., another for 0-7 st., one for 0-14 lb., one for 0-15 ozs., and one wheel for 0-15 drm. As these wheels have unequal number of numerals, the associated notches in the selector plates have different unit depth, as already explained above with reference to the units of pence denomination. Assuming that notches representing tons values have unit depth (1 ton=1 unit), notches representing cwt. will have

$$1 \times \frac{10}{20} = 0.5 \text{ unit depth}$$

those for st.

$$\frac{10}{8} = 1.25$$

those for lb.

$$\frac{10}{14} = 0.714$$

finally, notches representing oz. and drm., respectively, have unit depth of

$$\frac{10}{16} = 0.625$$

All notches shown in Figure 18 are appropriately designated, and it will be seen that, for instance, the right-hand slot in the selector plate 19 cwt. (upper bank) comprises two notches designated 10 cwt. and 5t.; they are of equal length for the reason stated above. It may be noted that the spacing between sensing pins 24 of the tons set of units is equal to the carriage shift, whereas the spacing between all other sensing pins is equal but smaller than the carriage shift.

It may be noted that in the specification and the claims the pounds notation is referred to as decimal denominations notwithstanding the fact that pounds are related to shillings and pence in a non-decimal manner, since each pounds de-

nomination is a decimal multiple of any other pounds denomination. For the same reason, decimal fractions of a penny may be referred to, for the purpose of this specification, as decimal denominations (obviously different from the pounds denominations). Pence are referred to as a non-decimal denomination distinct from the fractions of a penny, since not all pence digits are decimal multiples of the same digits of the decimal fractions. For instance 10d., is not equal to 0.1d. $\times$ 10, but to 1d. $\times$ 10. Similarly, tens of shillings and units of shillings are deemed to be, for the purpose of this specification, two separate non-decimal denominations, since the tens of shillings are not decimal multiples of the same digits of the units of shillings. Thus, ten times 2/- is not 20/-, but £1. The set-up factor to be entered into the result register, such as multiplicand, dividend, or divisor, is referred to in the appended claims generally as the "first factor," whilst the factor determined by the number of operating cycles and registered in the revolution register, such as multiplier or quotient, is referred to as the "second factor."

25 What I claim is:

1. In a calculating machine for non-uniform first factors comprising interrelated decimal and non-decimal denominations and for decimal second factors, set-up means for setting up the values 30 of the first factor, selector elements settable by said set-up means and each associated with a set-up value, each selector element comprising representations of digits of products formed by multiplication of the respective set-up value by the unit values of all denominations, within the machine capacity, of the second factor, said products being expressed in the non-uniform numerical system, a totalising register comprising a plurality of denominational registering elements, sensing elements each operatively associated with a denominational registering element and being spaced laterally of the register by a constant distance in the case of sensing elements 40 associated with registering elements of decimal 45 denominations and by a distance different to said constant distance in the case of sensing elements associated with non-decimal denominations, and a carriage movable in the direction parallel to the register in steps equal to said constant distance into a plurality of positions each associated with a denomination of the second factor, the said carriage serving to change the relative positions of said sensing means and of said selector elements, the said representations 50 being spaced laterally in accordance with said spacing of the sensing elements so that in each carriage position only those representations are aligned with said sensing elements which represent the product of the set-up factor by the unit 55 value of the particular denomination of the second factor associated with this carriage position.
2. In a calculating machine for non-uniform numerical systems comprising interrelated decimal and non-decimal denominations, means 60 for setting up the values of the non-uniform factor, a products register comprising a plurality of denominational registering elements, a plurality of sensing elements each operatively associated with a registering element, 65 a carriage movable in equal steps parallel to said register into a plurality of positions each associated with a denomination of the decimal second factor, the lateral spacing of the sensing elements associated with decimal denominations 70 being equal to the carriage step whilst the spac- 75

ing of the sensing elements associated with non-decimal denominations is different from the carriage step, conversion means mounted on said carriage and comprising one settable selector element for each set-up value, each selector element carrying physical representations of digits of products formed by multiplying the respective set-up value by unit values of denominations of the second factor and expressed in the non-uniform numerical system, each selector element being arranged on the carriage in a laterally fixed position, the said representations being laterally spaced on each selector element in accordance with said spacing of the sensing elements, in each carriage position only those representations being aligned with the sensing elements which represent the product of the set-up value by the unit value of the denomination of the second factor associated with this particular carriage position.

3. In a calculating machine for non-uniform numerical systems comprising interrelated decimal and non-decimal denominations, means for setting up the non-uniform factor, a totalising register comprising a plurality of denominational registering elements, a plurality of sensing elements each operatively associated with a registering element, a carriage movable in equal steps parallel to said register, each carriage position being associated with a denomination of the decimal second factor, the spacing of the sensing elements associated with decimal denominations being equal to said carriage step whilst the spacing of the sensing elements associated with non-decimal denominations is different from this step, conversion means mounted on said carriage and comprising one settable selector element for each set-up value, each selector element carrying representations of the respective set-up value multiplied by unit values of all denominations of the second factor, all selector elements associated with digits of the same set-up denomination being supported by a common structure laterally fixed in said carriage, the selector elements extending in their supporting structures parallel to the register in a plurality of banks, the said representations being laterally spaced on their selector elements in accordance with the said spacing of the sensing elements, so that in each carriage position only those representations are aligned with the sensing elements which represent the product of the set-up factor by the unit value of the denomination of the second factor associated with this particular carriage position.

4. In a calculating machine for non-uniform first factors comprising interrelated decimal and non-decimal denominations and for decimal second factors, set-up means for setting up the values of the first factor, selector elements settable by said set-up means and each associated with a set-up value, each selector element comprising representations of digits of products formed by multiplying the associated set-up value by the digit 1 of all denominations of the second factor, said products being expressed in the non-uniform numerical system, an axially fixed totalising register comprising a plurality of axially fixed denominational registering elements, a carriage movable in equal steps parallel to the register into a plurality of positions each associated with a denomination of the second factor, the said set-up means and the said selector elements being mounted on said carriage, and sensing elements each arranged in a laterally fixed position in operative association with a denominational regis-

tering element, the lateral spacing of sensing elements associated with decimal denominations being equal to the said carriage step whilst the spacing of sensing elements associated with non-decimal denominations is different to the carriage shift, the said representations being laterally spaced on their respective selector elements in accordance with said spacing of the sensing elements, in each carriage position only those representations being aligned with the sensing elements which represent the product of the first factor by the digit 1 of the particular denomination of the second factor associated with this carriage position.

5. In a calculating machine according to claim 1, a totalising register comprising a plurality of registering elements each associated with a decimal or non-decimal denomination, respectively, and settable selector elements each associated with a set-up value and each having representations of numerical values to be entered into respective registering elements of the said register, each representation being of a length proportional to the respective numerical value, the representation of the digit "1" of a decimal denomination being of a predetermined unit length whilst the representation of the digit "1" of a non-decimal denomination is equal to the said unit length multiplied by 10 and divided by the total number of numerical values in this particular non-decimal denomination.

6. A calculating machine for non-uniform numerical systems comprising interrelated decimal and non-decimal denominations, comprising means for setting up the values of the non-uniform factor, a totalising register comprising a plurality of registering elements each associated respectively with a decimal or non-decimal denomination, conversion means comprising one settable selector element for each set-up value, each selector element having physical representations of products formed by multiplication of the respective set-up value by the unit values of all denominations, within the capacity of the machine, of the decimal second factor, said selector elements being arranged on a plurality of banks extending parallel to said register a plurality of groups of sensing elements, each group being operatively associated with a denominational registering element and each sensing element within each group being operatively associated with a bank of selector elements, the distance between adjacent groups of sensing elements associated with decimal denominations being equal to a predetermined distance whilst the distance between any other adjacent groups of sensing elements is different from this predetermined distance, means for selecting representations associated with a desired denomination of the second factor comprising means for relatively displacing the conversion means and the sensing elements in the direction parallel to said register in equal steps substantially equal to the said predetermined distance, the said representations being adapted to represent, in each relative position, the product of the set-up factor by the unit value of the denomination of the second factor associated with this position, and means for entering the values represented by said representations and sensed by said sensing elements directly into the corresponding registering elements of the said totalising register.

7. A calculating machine according to claim 6, wherein the said settable selector elements comprise notched plates, all notched plates associ-

ated with the same set-up denomination being mounted in a common structure rockable around a shaft extending parallel to the said register, at least one of said shafts supporting several of said structures in fixed axial positions relatively to each other and to structures mounted on other shafts, each of said structures being operatively associated with the setting up means which when operated cause the respective structure to rock around its shaft to bring the notched plate associated with the respective set-up digit into a working position.

8. A calculating machine according to claim 6, wherein some of the said denominational registering elements are each operatively associated with a group of sensing elements, all sensing elements of a group being disposed in a plane at right angles to the axis of said register, one sensing element in each group being provided for each bank of said selector elements, a driving member operatively disposed between sensing elements of each group and the associated registering element being adapted to drive this registering element to an extent which is proportional to and controlled by the physical representation sensed by any sensing element of the respective group.

9. A calculating machine according to claim 6, wherein the sensing elements associated with registering elements reserved respectively for denominations of a decimal notation are spaced apart in the direction parallel to the said register by the said predetermined distance, whilst the distances respectively between sensing elements associated with non-decimal denominations, between sensing elements of non-decimal denominations and those of decimal denominations, and between sensing elements associated with different decimal notations are different from the said predetermined distance and any whole multiple thereof.

10. A calculating machine according to claim 6, wherein means are provided for rendering operative, in each of said relative positions, only those sensing elements which are associated with denominations of the product associated with this position.

11. A calculating machine according to claim 6, comprising groups of sensing elements, each group being associated with a denominational registering element of said totalising register and each sensing element within a group being associated with a bank of said selector elements and being disposed in line with a selector element on the respective bank when this selector element is set in the working position, a driving member operatively disposed between each group of sensing elements and the associated registering element being adapted to drive this registering element to an extent proportional to, and controlled by, the physical representations sensed by each sensing element of the respective group, a feeler operatively disposed between each driving member and the sensing elements of the respective group being adapted to operatively associate the driving member with each sensing element of the group in succession during each operating cycle of the machine.

12. A calculating machine according to claim 6, wherein each registering element is operatively associated with a driving member, and a feeler is pivotally mounted on each driving member except that member associated with the registering element of the highest denomination, said feelers being controlled by a parallelogram link-

age so as to move along substantially parallel lines while being aligned with the various banks of selector elements successively during each operating cycle of the machine.

5 13. A calculating machine according to claim 6, comprising driving members each operatively associated with a denominational registering element of the totalising register, feelers adapted to operatively associate said driving members with any one bank of said selector elements, a main operating shaft, means fixed in spaced relationship on this shaft for operating said driving members once for each bank and for successively aligning the feelers with the various banks during each revolution of this shaft, to sense successively the physical representations on the selector elements of each bank and to enter the sensed values into the respective registering elements, and manually controlled means for driving the main operating shaft repeatedly in conformity with digital values of the second factor entering into the calculation.

14. A calculating machine according to claim 6, wherein means are provided for operating the carry device of the totalising register after each bank of selector elements has been sensed.

15. A calculating machine for the Sterling numerical system, comprising means for setting up the sterling factor including pounds, shillings, pence, and fractions of a penny, a totalising register comprising registering elements each associated with a denomination of pounds, shillings, pence, or decimal fractions of a penny, respectively, conversion means comprising one settable selector element for each set-up value, each selector element having representations of the associated set-up value multiplied by successive powers of 10, the said selector elements being arranged in three banks extending parallel to said register on 40 a carriage movable parallel to the register in equal steps into a plurality of positions each associated with a denomination of the decimal second factor, groups of three sensing elements, one element for each of said banks, each group of sensing elements being operatively associated with a registering element and being located in a laterally fixed position, the lateral distance between any two adjacent groups of sensing elements associated respectively with pounds denominations or 50 with denominations of decimal fractions of a penny being equal to said carriage step whilst the lateral distance between any other adjacent groups of sensing elements is equal but different from the carriage step, the distance between 55 the groups of sensing elements associated respectively with units of pounds denomination and with tenths of a penny denomination being different from a whole multiple of the carriage step, the representations on said selector elements being spaced laterally in accordance with 60 said spacing of the groups of sensing elements so that in each carriage position only the representations of that power of 10 of the set-up factor are aligned with the sensing elements which 65 correspond to the denomination of the second factor associated with this particular carriage position, means for entering the values sensed by any of said sensing elements directly into the respective registering elements of the said totalising register during each operating cycle, a revolution register comprising a plurality of decimal registering elements each associated with a denomination of the second factor, and means for entering the number of operating cycles in 70 each carriage position into that registering element.

21

ment of the revolution register which is associated with the respective denomination of the second factor.

16. A calculating machine according to claim 6, wherein the said means for entering the values represented by said physical representations into the totalising register comprise driving members each operatively disposed between a

22

group of said sensing elements and the associated denominational registering element, said driving members being connected to the respective registering elements by gearing of the same ratio irrespective of the number of digital values in the denominations with which the registering elements are respectively associated.

DANIEL BROIDO.
